UNITED STATES PATENT OFFICE

1,958,249

REFRIGERATING SYSTEM

Paul F. Schlingman, Schenectady, N. Y., assignor
to General Electric Company, a corporation
of New York

Application May 20, 1933, Serial No. 672,031

4 Claims. (Cl. 62--178)

This invention relates to refrigerating systems and is more particularly concerned with the refrigerant employed therein.

The trifluoro derivative of dimethyl ketone (trifluoro acetone) $CF_3\text{-CO-CH}_3$ possesses properties which make it admirably suitable for use as a refrigerant, especially in systems employing a low pressure type refrigerant. This material boils at about 22° C. when subjected to atmospheric pressure is relatively stable, and its specific gravity is about 1.29. It is not miscible with lubricating oils ordinarily used in refrigerating systems and is relatively non-inflammable. It is non-toxic and has a mild, pleasant odor. These properties are highly desirable in a refrigerant.

The trifluoro derivative of dimethyl ketone may be prepared by either one of two general methods. One of these methods involves the decomposition of trifluoro-acetoacetic ester by heating with dilute sulphuric acid and the other method consists of the condensation of ethyl trifluoroacetate and ethyl acetate in the presence of sodium in an ethereal solution to form sodium trifluoracetacetate which is then decomposed by an excess of dilute sulphuric acid.

The accompanying drawing forming part of this application illustrates diagrammatically a refrigerating system comprising a compressor,

condenser and evaporator. In this system the trifluoro acetone passes through the cycle of first being compressed by the compressor, then passes to the condenser where it is cooled and condensed into a liquid which passes to the evaporator, the liquid refrigerant vaporized in the evaporator being finally returned to the compressor to complete the cycle.

What I claim as new and desire to secure by Letters Patent of the United States, is:

1. The process of refrigeration which comprises condensing the trifluoro derivative of dimethyl ketone and then evaporating said derivative. 65
2. The process of refrigeration which comprises circulating through a refrigerating system including a compressor, a condenser and an evaporator, the trifluoro derivative of dimethyl ketone and successively condensing and evaporating said derivative. 70
3. The process of transferring heat which comprises condensing trifluoro acetone and then 75 evaporating it.
4. The process of transferring heat through a refrigerating system which comprises condensing trifluoro acetone and then evaporating it within the system. 80
